UNITED STATES PATENT OFFICE.

JOHN N. HARRISON, OF OTTAWA, KANSAS, ASSIGNOR TO THE CAPITAL IRON WORKS, OF TOPEKA, KANSAS, A CORPORATION OF KANSAS.

DESIGN FOR A METALLIC CURB.

SPECIFICATION forming part of Design No. 35,760, dated February 18, 1902.

Application filed January 4, 1902. Serial No. 88,472. Term of patent 14 years.

To all whom it may concern:

Be it known that I, JOHN N. HARRISON, a citizen of the United States, residing at Ottawa, in the county of Franklin and State of Kansas, have invented and produced a new and original Design for Metallic Curbs, of which the following is a specification, reference being had to the accompanying drawings, forming a part hereof.

10 In the accompanying drawings, Figure 1 represents a perspective view of one piece of curbing constructed substantially in accordance with this design; Fig. 2, a perspective view of one end of the curbing—the left-hand 15 end shown in Fig. 1; and Fig. 3, a broken plan sectional view, taken on line 3 of Fig. 1, looking in the direction of the arrow.

As shown in the drawings, the leading or material features of my design consist in a 20 series of ribs A and grooves or corrugations B, disposed or arranged, as shown in Figs. 1 and 3, to form the body of the curb, the said

ribs being substantially convex, as shown in cross-section, and the said grooves or corrugations arranged between the same, as shown 25 particularly in Fig. 3. The lower part of the curb is provided with an outwardly-extending flange C, as shown in Figs. 1 and 2, and the upper part with an outwardly-extending flange or bead D, substantially convex in con- 30 tour, as shown in the drawings.

Having thus described my invention, what I claim as new, and desire to secure by Letters Patent, is—

The design for a curb, as herein shown and 35 described.

In testimony whereof I have signed my name to this specification in the presence of two subscribing witnesses.

JOHN N. HARRISON.
